PAGE 2

—FIG. 2.—

—FIG. 3.—

—FIG. 4.—

FIG. 1 is a front perspective view of a guitar body, showing my new design;

FIG. 2 is a front elevational view;

FIG. 3 is a side perspective view; and

FIG. 4 is a rear perspective view thereof.

My design is characterized by a guitar having horns which are pointed inwardly and are of different heights in combination with a guitar body which is round and smooth at all points thereof and having a recessed area in the front face thereof all as shown.

I claim:

The ornamental design for a guitar body, substantially as shown and described.
